UNITED STATES PATENT OFFICE.

RANSOM C. WRIGHT, OF PHILADELPHIA, PENNSYLVANIA, AND FRANK E. STEBBINS, OF WASHINGTON, DISTRICT OF COLUMBIA; SOPHIE JANE WRIGHT, EXECUTRIX OF SAID RANSOM C. WRIGHT, DECEASED, ASSIGNOR TO SAID FRANK E. STEBBINS.

CAR-TRUCK.

1,036,768.

Specification of Letters Patent. Patented Aug. 27, 1912.

Application filed October 19, 1905, Serial No. 283,404. Renewed January 15, 1912. Serial No. 671,368.

To all whom it may concern:

Be it known that we, RANSOM C. WRIGHT and FRANK E. STEBBINS, citizens of the United States, residing at Philadelphia, in the county of Philadelphia and State of Pennsylvania, and Washington, District of Columbia, respectively, have invented certain new and useful Improvements in Car-Trucks, of which the following is a specification.

Our invention relates to car trucks, and especially to the frames thereof and also to the combination of the frame with the journal boxes and springs.

Our objects are the production of a frame which can easily and cheaply be manufactured without the use of special appliances and can be repaired with equal facility, which shall be of ample strength at the upper end portions thereof where the weight is transmitted to the springs, which shall have the jaws or legs of the pedestals open at the bottom, and which in the preferred form shall allow the removal of an axle, a pair of wheels and two journal boxes by jacking up the end of the frame a short distance.

A further object is the provision of a combined wearing shoe and outer removable pedestal leg. And the final object is to form the main portions of the sides of flanged beams preferably rolled and to so fashion the ends thereof that very little labor will be involved in adapting them for the reception of cast metal pedestals.

With these ends in view, our invention consists in certain novelties of construction and combinations of parts hereinafter set forth and specified in the claims.

The accompanying drawings illustrate three examples of the physical embodiment of our invention constructed according to the best modes we have so far devised for the practical application of the principles.

Figure 1 is a side view of a car truck in elevation with the cast metal portion of the pedestal at the left hand in vertical section. Fig. 2 is a one-half top plan view of Fig. 1, except that the cast metal pedestal is removed at the left hand end of the side piece; the other half of the frame being of identical construction is not shown. Fig. 3 is a view in elevation of the right hand end of the frame illustrated in Figs.

1 and 2. Fig. 4 is an enlarged section on line $x-x$ of Fig. 1. Fig. 5 is a top plan view of the cast metal pedestal. Figs. 6, 7 and 8 illustrate another species of frame construction, Fig. 6 being a side view with one cast metal pedestal removed, Fig. 7 a half top plan view of Fig. 6, and Fig. 8 an end view in elevation of the pedestal. Figs. 9, 10 and 11 show a third species, similar to the second species, but wherein the main portions of the sides are of rolled channel beams.

Referring to all the species, the numeral 1 designates the transoms which unite the parallel sides pieces adjacent their centers, said transoms in this instance being of channel beams spaced apart; 2, tie pieces which unite the transoms adjacent their centers; 3, top plates riveted to the flanges of the transoms at their centers; 4, the rolled flanged beams which constitute the side pieces, Sheets 1 and 2 showing them as I beams and Sheet 3 as channel beams; 5, top gusset plates, and 6 bottom gusset plates which are riveted to the flanges of the side pieces and the transoms; 7, connection angles which are riveted to the webs of the side pieces and the webs of the transoms; 8, the lower straight and unbent end portions of the side pieces cut off square through the web and flanges or flange, said end portions abutting the journal boxes or inner bearing flanges of the pedestals; 9, the upper upwardly bent end portions of the side pieces shown extending over the tops of the journal boxes in each of the three species, though in some cases, when so desired, they may end on top of the boxes; 10, the wheels and axles; 11, the journals; 12, the journal boxes with their opposite vertical sides recessed or provided with flanges, in a manner well known; 13, helical springs upon the tops of the journal boxes; 14, the inner bearing flange of the cast metal pedestal; 15, the seat or pocket for the upper end or ends of the spring or springs; 16, the web portion of the pedestal at right angles to the inner bearing flange; 17, the vertical web portion which extends over the spring seat or pocket, both of said web portions being secured to the upper and lower web portions of the end of a side piece by rivets passed through the webs of each, as shown; 18, a seat in the pedestal for the reception of the lower flange of the

side piece; 19, the lower portion of the inner pedestal jaw perforated to receive a tie bolt; 20, a flange engaging the lower flange of the side piece; 21, rivets which are passed 5 through said flanges—the inner flange of the I beam in Sheets 1 and 2, and the outer or single flange in Sheet 3, as shown; 22, a spacing piece; and 23 is a tie bolt.

The cast metal pedestal shown on Sheet 10 1 has a composite outer leg or jaw comprising an integral portion 24 downwardly extended from the outer edge of the pedestal head or spring seat or pocket to a position preferably adjacent or below the center of 15 the journal box, or, in other words, this portion 24 hooks over the journal box, a longitudinal recess or slot 25 being formed in the downwardly projecting portion 24 and said slot is preferably V-shaped and deeper 20 at the bottom than at the top part of said projection, as shown, though it may be of any other suitable shape; and the combined removable leg and wearing shoe 26 having the flange 27, web 28 at right angles to the flange, and the perforated lower end portion for the tie bolt. This wearing shoe and leg 26 may be of wrought metal and forged to shape. The web 28 of the leg fits within the recess or slot 25 in the part 24, 30 and the said leg and part 24 are united by bolts 29 passed through both elements as shown. When the nuts 30 are tightened, the removable leg will be held fixed by frictional contact relative to the projecting portion 35 24 so it cannot move in any direction. The flange 27 is located inside the projecting portion 24 and is in frictional contact with the journal box, and the upper portion of web 28 is tapered so it can easily be inserted and removed from the tapered slot or recess 25. When a pair of wheels is to 40 be removed the tie bolt and bolts 29 are withdrawn, the leg 26 lowered from its seat, and the frame jacked up until the ends of 45 the projections 24 are above the tops of the journal boxes. The cast metal pedestals shown on Sheets 2 and 3 are of substantially identical construction, the outer leg or jaw 31 in each species being integral with the 50 spring seat or pocket or head of the pedestal and comprised of a bearing flange 32, a web 33 and an enlargement 34, the lower end of the leg also being perforated to receive the tie bolt.

55 In fashioning the rolled flanged beam for a side piece the lower flange and web may be cut on the line $a-b$ (see Fig. 6), the upper flange and web on line $c-d$, the web cut longitudinally on the line $e-b-d$, a portion of 60 the web above line $d-b$ removed, and the remaining portion thereof with the upper flange then bent upwardly to the position shown in Fig. 6, where the top flange of the upper projecting end portion is in a 65 plane substantially parallel with but above

the plane of the top flange of the beam adjacent the transom ends. After both ends have been similarly fashioned, the holes for the reception of the various rivets are punched or drilled in the entire beam.

70 From the foregoing description taken in connection with the drawings it becomes clear that we have produced truck frames which fulfil the conditions set forth as the objects or purposes of our invention. The 75 ends of the side pieces can easily and cheaply be fashioned for the reception of the cast metal pedestals; when the pedestals which preferably have integral spring seats or pockets have been riveted in position, there will be ample strength on the line $t-t$ where the weight is transmitted to the top end of the helical spring or springs 13; and the removable portion of the outer pedestal leg or jaw permits the 80 rolling out of a pair of wheels by jacking up the frame a short distance. Moreover, should the outer removable leg become excessively worn, another can be substituted.

85 Minor changes and modifications may be 90 introduced in the practical application of our improvements, as, for instance, the lower portion of the inner pedestal jaw may be made separate, the shape of the 95 spring seat or pocket be altered, and the upper end of the removable part of the outer jaw in the first species interlock with the downwardly projecting portion in a different manner. Such and other modifications we shall not regard as substantial 100 departures.

What we claim is:

1. The combination in a car truck frame, of a transom or transoms located between the pairs of wheels; side pieces consisting 105 of flanged beams united adjacent their centers to the ends of the transom or transoms, each end of each side piece being fashioned to have a lower straight portion embracing a part of the lower flange and web, and an upwardly bent upper portion embracing a part 110 of the upper flange and web, said upper portion projecting beyond the lower portion; and cast pedestals riveted to the upper and lower portions of each end of the side piece; each of said pedestals having flanged jaws or legs open at the bottom; and the upwardly bent upper portions of the side piece being substantially straight and ending adjacent the spring seats or pockets. 115

120 2. The combination in a car truck frame, of a transom or transoms located between the pairs of wheels; side pieces consisting of flanged beams united adjacent their centers to the ends of the transom or transoms, each end of each side piece being fashioned to have a lower straight portion embracing a part of the lower flange and web, and an upwardly bent upper portion embracing a part 125 of the upper flange and web, said upper 130

portion projecting beyond the lower portion; and cast metal pedestals riveted to the upper and lower portions of each end of a side piece; each of said pedestals having flanged jaws open at the bottom and a seat or pocket integral with the pedestal for the upper end of a spring.

3. The combination in a car truck frame, of a transom or transoms located between the pairs of wheels; side pieces consisting of flanged beams united adjacent their centers to the ends of the transom or transoms, each end of each side piece being fashioned to have a lower straight portion embracing a part of the lower flange and web, and an upwardly bent upper portion embracing a part of the upper flange and web, said upper portion projecting beyond the lower portion; and cast metal pedestals riveted to the upper and lower portions of each end of a side piece; each of said pedestals having jaws open at the bottom and a lower portion of the inner pedestal jaw 19 riveted to the lower flange of the side piece; and said upwardly bent upper portions of the side piece being substantially straight and secured to the pedestal heads only adjacent the spring seats or pockets.

4. The combination in a car truck frame, of a transom or transoms located between the pairs of wheels; side pieces consisting of flanged beams united adjacent their centers to the ends of the transom or transoms, each end of each side piece being fashioned to have a lower straight portion embracing a part of the lower flange and web, and an upwardly bent upper portion embracing a part of the upper flange and web, said upper portion projecting beyond the lower portion; and cast metal pedestals riveted to the upper and lower portions of each end of a side piece; each of said pedestals having jaws open at the bottom, a web portion 16, a web portion 17, a spring seat or pocket integral with the pedestal, and a lower portion of the inner jaw extended below the end of the side piece.

5. The combination in a car truck frame, of a transom or transoms located between the pairs of wheels; side pieces consisting of flanged beams united adjacent their centers to the ends of the transom or transoms, each end of each side piece being fashioned to have a lower straight portion embracing a part of the lower flange and web, and an upwardly bent upper portion embracing a part of the upper flange and web, said upper portion projecting beyond the lower portion; and cast metal pedestals riveted to the upper and lower portions of each end of a side piece; each of said pedestals having bearing flanges for a journal box and a seat or recess 18 for the flange of the lower straight end portion 8 of the side piece.

6. The combination in a car truck frame,

of a transom or transoms located between the pairs of wheels; side pieces consisting of flanged beams united adjacent their centers to the ends of the transom or transoms, each end of each side piece being fashioned to have a lower straight portion embracing a part of the lower flange and web, and an upwardly bent upper portion embracing a part of the upper flange and web, said upper portion projecting beyond the lower portion; and cast metal pedestals riveted to the upper and lower portions of each end of a side piece; each of said pedestals having jaws open at the bottom and riveted to one surface only of the end of a side piece with which it is in frictional contact.

7. The combination in a car truck frame, of a transom or transoms located between the pairs of wheels; side pieces consisting of flanged beams united adjacent their centers to the ends of the transom or transoms, each end of each side piece being fashioned to have a lower straight portion embracing a part of the lower flange and web, and an upwardly bent upper portion embracing a part of the upper flange and web, said upper portion projecting beyond the lower portion; and cast metal pedestals riveted to the upper and lower portions of each end of a side piece; each of said pedestals having a composite outer jaw or leg comprising an upper part integral with the pedestal which hooks over the journal box when the latter is in place and a removable lower part.

8. A side piece for a car truck frame consisting of a flanged metallic beam having at each end a lower straight portion 8 embracing a part of the lower flange and web, and an upper upwardly bent portion 9 embracing a part of the upper flange and web and projecting beyond the lower portion, and cast metal pedestals having jaws open at the bottom riveted to the webs of the lower and upper portions of the ends of the beam.

9. A side piece for a car truck frame consisting of a flanged metallic beam having at each end a lower straight portion 8 embracing a part of the lower flange and web, and an upper upwardly bent portion 9 embracing a part of the upper flange and web and projecting beyond the lower portion, and cast metal pedestals having jaws open at the bottom and each pedestal riveted to the webs of the upper and lower portions and the flange of the lower portion; said upwardly bent portions 9 ending adjacent the spring seats or pockets.

10. A side piece for a car truck frame consisting of a flanged metallic beam having at each end a lower straight portion 8 embracing a part of the lower flange and web, and an upper upwardly bent portion 9.

9 embracing a part of the upper flange and web and projecting beyond the lower portion, and cast metal pedestals riveted to the ends of the beam, each pedestal having jaws 5 open at the bottom, and an integral spring seat or pocket for strengthening the pedestal on the line $t-t$ where the weight is transmitted to the spring.

11. A side piece for a car truck frame consisting of a flanged metallic beam having at each end a lower straight portion 8 embracing a part of the lower flange and web, and an upper upwardly bent portion 9 embracing a part of the upper flange and web and 15 projecting beyond the lower portion, and cast metal pedestals having jaws open at the bottom riveted to the ends of the beam upon one surface only thereof.

12. A side piece for a car truck frame consisting of a flanged metallic beam having at each end a lower straight portion 8 embracing a part of the lower flange and web, and an upper upwardly bent portion 9 embracing a part of the upper flange and web 20 and projecting beyond the lower portion, and cast metal pedestals riveted to the ends of the beam, each of said pedestals having an outer jaw or leg comprised of an upper part hooking over the journal box when in 25 place and a removable lower part for the purpose specified.

13. A side piece for a car truck frame consisting of a flanged metallic beam having at each end a lower straight portion 8 embracing a part of the lower flange and web, and an upper upwardly bent portion 9 embracing a part of the upper flange and web and projecting beyond the lower portion, and cast metal pedestals riveted to the ends of 30 the beam, each of said pedestals having an outer jaw or leg comprised of an upper slotted part hooking over the journal box when in place and a removable lower part fitting the slot in the upper part and secured in 35 place by a bolt or bolts, in substance as set forth.

14. A cast metal pedestal comprising flanged jaws open at the bottom and provided with means to receive a tie piece or 50 bolt, webs 16 and 17, and a spring seat or pocket, and said pedestal riveted to the end of a flanged beam, the upper portion of which beam extends over the seat or pocket for the spring and the lower part abuts the inner bearing flange of the pedestal.

15. A cast metal pedestal comprising flanged jaws open at the bottom and provided with holes for a tie bolt, a seat or 55 pocket for a spring, a single web 16 at right angles to the inner bearing flange, a web 17 above the spring seat or pocket, and a perforated flange at the lower portion of the inner pedestal jaw for attachment to the flange of a side piece.

16. A cast metal pedestal comprising 65 flanged jaws open at the bottom, a seat or pocket for a spring, a single web 16, and a web 17 above the spring seat; the lower portion of the inner pedestal leg having a seat or recess 18 bounded by the flange 20 and 70 the lower edge of the web 16 to receive the flange of a side piece.

17. A cast metal pedestal having an outer jaw or leg comprised of an upper slotted or recessed portion which is adapted to hook 75 over a journal box, and a lower flanged portion engaging the slot and removably secured in position by a bolt or bolts; the upper part of the flange of the lower portion being located inside the slotted upper 80 portion of the leg.

18. A cast metal pedestal having a seat or pocket for a spring, an outer jaw comprising a slotted portion extended downwardly from the spring seat or pocket and adapted 85 to hook over a journal box, and a lower flanged portion with its top end located between the downwardly projecting portion and the journal box when the latter is in place, and removably secured in position by 90 a bolt or bolts.

19. A metallic pedestal having an outer jaw or leg comprising an upper portion integral with the pedestal and projecting downwardly and adapted to hook over a 95 journal box when the latter is in place, and a lower flanged portion having a hole for a tie bolt; said lower portion interlocking with the upper portion and removably held in position by a bolt or bolts.

20. A metallic pedestal having an outer leg comprising the slotted portion 24 integral with the pedestal and hooking over the journal box when the latter is in place, and a lower portion having a wearing flange 105 27 and web 28, the upper part of the latter fitting within the slot of the upper portion 24 and removably held in position by the bolt or bolts passing through holes in the upper and lower portions.

21. A metallic pedestal having an outer leg with an upper portion 24 with a tapering slot, and a lower portion having a wearing flange and a tapered web, the web fitting the tapering slot in the part 24, and the 115 parts united by a bolt or bolts.

22. A metallic pedestal having an outer leg comprising an upper portion 24 with a V-shaped slot, a lower portion with a wearing flange and V-shaped web to fit the V-shaped slot, and a bolt or bolts uniting said upper and lower portions.

23. A metallic pedestal having an outer leg comprised of upper and lower portions united by a bolt or bolts, said upper portion 125 hooking over the journal box when in place, and said lower portion interlocking with said upper portion and provided with a

wearing flange, the upper part of which is located between the said upper portion and the journal box.

24. The combination in a car truck frame, 5 of a transom or transoms, flanged metallic side pieces united to the transom or transoms, and cast metal pedestals having jaws open at the bottom; each side piece having at each end a lower flanged portion, and an 10 upper flanged portion projecting beyond the said lower portion; and a pedestal secured to the upper and lower flanged portions at each end of a side piece; said upper

flanged portions of the side piece ending adjacent the tops of the spring seats or 15 pockets.

In testimony whereof we affix our signatures in presence of two witnesses.
